MEANS FOR PROFILING TURBINE AND COMPRESSOR-BLADING

Walter Edward Dazeley, Twiston, near Clitheroe, England, assignor to Rolls-Royce Limited, Derby, England, a British company

Application October 31, 1947, Serial No. 783,310
In Great Britain November 1, 1946

4 Claims. (Cl. 18—1)

This invention relates to the manufacture of turbine- and compressor-blading and is more particularly concerned with the profiling of such blading.

The object of this invention is to provide an apparatus for producing quickly and accurately and without the exercise of a high degree of skill on the part of the operator a master form from which the blading is profiled by any suitable method. A master form when produced will be used, for example, for the purpose of sinking dies for the production of the blading as by coining or by stamping or alternatively will be used as the master form in a copying machine for machining blades. Such a machining operation will conveniently be limited to a finishing operation of a blade blank which has been roughly pre-formed, for example, by forging, casting or coining methods.

It will be appreciated that the rapid and accurate production of master forms for use in the production of turbine- and compressor-blading will greatly facilitate the manufacture of the blading, particularly in the case of blading for multi-stage turbine and compressor in which the blade form varies from stage to stage of the turbine or compressor.

This invention also includes apparatus for carrying out the steps of profiling the master form and such apparatus may comprise a base, a slider supported on the base for movement parallel to the base, a second slide carried by the first slide for movement in a plane substantially at right angles to the base and a scraper-device carried on the second slide. Preferably the scraper-device is pivoted to the second slide so as to be capable of a canting or tilting movement about an axis substantially parallel to the direction of movement of first said slide.

In using such apparatus a base-plate or the like for the master form will be positioned on the base of the apparatus so that the templates carried by the master form base-plate lie in substantially vertical planes parallel to the direction of movement of first said slide; the contour of the profiles on the templates then represent ordinates in planes at right angles to the base of the apparatus and the movement of the second slide and the tilting movement of the scraper-device jointly accommodate changes in the vertical ordinates of the templates.

According to a further feature of the apparatus, the base-plate of the master form conveniently comprises a flat plate with side walls upstanding from its upper surface to provide a

box-like structure within which the templates are located, and the templates have straight bottom edges in contact with the upper surface of the base-plate and upper profiled edges exposed to the contact of the scraper-device. The box-like structure provides a receptacle for a hard, quick-drying non-shrinking cement which may be that known under the registered trademark "Calestone" and in certain cases it is proposed that the whole of the space within the receptacle should not be filled with cement but at least partly occupied by a roughly machined block to which the cement adheres.

One construction of apparatus for producing a master form by the method of this invention will now be described with reference to the accompanying drawings in which:

Figure 1 is a front elevation of the apparatus;
Figure 2 is a side elevation of the apparatus taken partly in section on the line 2—2 of Figure 1.

Figure 3 is a perspective view of a master form produced by the apparatus illustrated in Figures 1 and 2; and,

Figure 4 is a perspective view of a steel die-stamping block produced from the master form shown in Figure 3.

Referring to Figures 1 and 2, there is illustrated an apparatus suitable for producing master forms for turbine- or compressor-blades of which the profile of the concave or convex faces of the blade is defined by a series of straight lines drawn from the root to the tip of the blade and lying in planes parallel to one another.

In such a blade, the individual lines defining one surface of the blade thus all lie in planes parallel to a common plane. The common plane for the one surface is not however necessarily the common plane for the other surface.

The apparatus comprises a substantially rectangular base-plate 10 having a machined upper surface. On one end of the base 10 there is a pillar block 11 formed with a machined bore 12, the axis of which lies parallel to the machined surface of the base-plate 10 and extends substantially lengthwise thereof, midway across the width of the base-plate. The bore is fitted at each end with accurately machined lining bushes 13 constituting the slide for machined circular-sectioned slide-bar 14. The slide-bar 14 is formed axially thereof with a key-way 15 which is engaged by a pin 16 mounted in the pillar-block 11 and extending into the bore 12, so that its extremity projects into the key-way 15. Thereby the slide-bar 14 is located angularly

within the bore 14, and is permitted to slide within the bore. The length of the key-way 15 determines the extent by which the slide-bar can move within the bore.

One end of the slide-bar 14 which extends from the bore 12 at a point approximately half way along the length of the base-plate 10, carries a bracket 17 formed with vertical guides 18, which may be, for example, of dove-tail section. A slide 19 is engaged on the guides 18 and is connected at its upper end by a link 20 to a lever 21 pivoted at the upper end of the bracket 17, the lever 21 carrying on its opposite end a counter-weight 22 for balancing the slide 19.

The slide 19 has pivoted to it a scraper-device 23 which can tilt about an axis parallel to the axis of the slide-bar 14. The lower edge 24 of the scraper 23 is chamfered and is straight.

It will be appreciated from the above description that the edge 24 of the scraper-device 23 has three possible freedoms of movement, namely—

(a) A movement in a plane parallel to the base-plate by virtue of the sliding movement of the slide-bar 14.

(b) A movement in a plane at right angles to the surface of the base-plate by virtue of the sliding movement of the slide 19, and

(c) A canting or tilting movement about its pivot 30 which is at right angles to the edge 24 and substantially parallel to the surface of the base-plate 10.

The edge 24 can thus be constrained to sweep out any surface defined by a series of straight lines located in a series of planes which are parallel to the plane of the scraper-device 23.

The master form is produced in a box-like structure which comprises a base-plate 26, the lower surface of which is machined to provide accurate contact with the upper surface of the base-plate 10, and is formed in the lower surface with recesses to engage a pair of dowel pins 25 to locate the box-like structure on the base-plate 10. The upper surface of the base-plate 26 of the box-like structure is machined to be parallel with its lower surface and has supported on it a pair of side-walls 27 between which extend a pair of templates 28. These templates have their upper edges chamfered and formed with a contour corresponding to the contour of one surface of the blade being produced, that is, either the concave or the convex surface, respectively at two stations along the length of the blade. For example, the upper edges of the templates may be given a profile to correspond respectively to that at the root and tip of the blade. Thus, if the scraper-device 23 is caused to move with its edge 24 in contact with the upper edges of the templates 28 the straight edge 24 will sweep out a surface representing the profile of either the concave or convex surface of the blade being produced.

To produce the master form with this apparatus the box-like structure, if desired, provided with end walls 29, is filled with a hard, quick-drying non-shrinking cement such as "Calestone" or a like material and the box is located on the base-plate 10 by engaging dowels 25 in the recesses in the base-plate 26. The scraper-device is then drawn manually across the upper surface of the box-like structure with the edge 24 of the scraper-device in contact with the upper profiled edges of the templates 28, thus giving the cement within the box-like receptacle the desired profile,

as will be seen from Figure 3, in which the cement filling is indicated by reference numeral 31.

When the cement has hardened a master form is obtained which can be used to produce a steel die-stamping block such as that illustrated in Figure 4, or may be used for producing dies for coining blades or may be used as a master profile in a copying machine for machining blades. This machine may, if desired, be a final machine of roughly formed blanks.

For any blade two master forms will be produced one for profiling the concave blade surface and the other for the convex blade surface.

It will be appreciated that with the apparatus of this invention a master form can be rapidly and accurately produced with very little skill thus facilitating manufacture of compressor- and turbine-blades.

I claim:

1. Apparatus for producing an accurately-shaped master form for use in the manufacture of turbine and compressor blades, comprising a base, a box structure to receive a non-shrinking, settable material positively located on said base and having a pair of side walls at right angles to the base and between the side walls a pair of templates having their upper edges respectively contoured to conform to the desired blading section at two stations spaced along the length of the blade, a pillar carried on said base, a slide bar mounted in the pillar for movement parallel to said base and to the templates of the box structure, a slide carried by the slide bar and arranged for movement at right angles to said base, and a scraper carried on the slide with a scraper edge at right angles to the directions of movement of the slide bar, said scraper being movably mounted on said slide for edgewise movement relatively to the templates for permitting the scraper to conform to the contour of the upper edges of the templates for shaping the surface of the settable material in the box structure.

2. Apparatus for producing an accurately-shaped master form for use in the manufacture of turbine and compressor blades, comprising a base, a box-structure to receive a non-shrinking, settable material positively located on said base and having a pair of side walls at right angles to the base and between the side walls a pair of templates having their upper edges respectively contoured to conform to the desired blading section at two stations spaced along the length of the blade, a pillar carried on said base, a slide bar mounted in the pillar for movement parallel to said base and to the templates of the box structure, a slide carried by the slide bar and arranged for movement at right angles to said base, and a scraper carried on the slide with a scraper edge at right angles to the directions of movement of the slide bar and the slide to be guided by said templates to shape the surface of the settable material in the box structure, said scraper being pivoted on the slide to be tiltable about an axis which is parallel to the direction of movement of the slide bar.

3. Apparatus for producing an accurately-shaped master form for use in the manufacture of turbine and compressor blades, comprising a box structure to receive a non-shrinking, settable material having a pair of side walls and between the side walls a pair of templates having their upper edges respectively contoured to conform to the desired blading section at two stations spaced along the length of the blade, a slide bar mounted above and for crosswise movement above

said box adapted to move from side to side of said box, a slide carried by said slide bar and arranged for movement at substantially right angles to the direction of movement of the slide bar, a scraper carried on said slide having a scraper edge positioned to engage the edges of said templates, said scraper being pivoted on the slide to be tilttable about an axis which is substantially parallel to the direction of movement of the slide bar.

4. An apparatus for producing an accurately-shaped master form for use in the manufacture of turbine and compressor blades, comprising a container for a non-shrinking, settable material, a pair of templates in said container spaced from one another and having their upper edges contoured differently to conform to blading sections at two stations spaced along the length of the blade, a scraping blade arranged substantially at right angles to said templates and of a length to simultaneously and continuously contact the differentially contoured upper edges of said templates as the scraping blade is moved therealong, a carrier for supporting and moving said scraping blade lengthwise along said upper edges of the templates, means for urging the scraping blade toward said upper edges of the templates during its movement along such edges, and means for

10

15

20

25

pivottally mounting said scraping blade to rock edgewise to permit local portions of the blade above the respective templates to accurately follow the differentially formed contours of the upper edges of said templates whereby the scraping blade wipes over the material in the container to produce a molded material having an upper surface in exact replica of the corresponding surface of the blade to be formed.
